PRESSING MACHINE

Samuel Goldstein, New York, N. Y.

Application July 23, 1938, Serial No. 220,862

7 Claims.

(Cl. 38—32)

This invention relates to pressing machines of the character used for pressing articles of wearing apparel or portions thereof, such as seams, pockets, arm-hole portions or the like, and has for its main object the provision of a machine of this character which will effectively perform the functions for which it is intended with a minimum of manual effort on the part of the operator.

Another object of the invention is to provide means in a machine of this character, for either automatically or manually applying a vacuum or "suction" to the interior of the buck upon which the article being pressed is supported, for the prompt removal of the moisture from the garment, upon lifting movement of the pressing iron.

Another object of the invention is to provide in a machine of the character described, an improved means for regulating the extent of pressure imposed by the pressing iron on the buck, such adjustable means being available at a convenient location on the machine whereby it may be operated without inconvenience on the part of the operator.

Other objects of the invention are attained by the improved machine, a particular description of which will be set forth hereinafter and be more particularly pointed out in the claims appended hereto.

In the accompanying drawings forming a part hereof, Fig. 1 is a side elevation of the improved machine with some parts in section, and other parts broken away, to disclose construction; Fig. 2 is a plan view of the machine; Fig. 3 is a vertical sectional view through the machine; Fig. 4 is a sectional view on the line 4—4 of Fig. 3, looking in the direction of the arrows; and Fig. 5 is a sectional view on the line 5—5 of Fig. 3, looking in the direction of the arrows.

The elements of the machine are either mounted in or supported by the frame which includes a horizontal top or table portion 1, sides 2, supporting feet 3 and a front plate 10, the entire frame being preferably, but not necessarily in the form of a casting. Mounted above the top of the table 1 on a hollow pedestal or similar support 11 is the buck 4 which may be of any suitable shape to effectively accommodate the garment or portions of the garment or other article to be pressed. The buck 4 is of hollow construction and is formed with an upper chamber 5 and a lower steam chamber 7. The top of the buck is provided with a plurality of perforations 6 in the conventional manner through

which moisture may pass to enter chamber 5. Leading into the lower chamber 7 is pipe or tube 8 through which steam, emanating from a suitable source, enters chamber 7 and heats the buck, the condensation passing out of the buck through pipe or tube 9.

Mounted above the buck is a pressing iron 12 heated by steam, gas, electricity or other suitable source of heat, and provided with an operating handle 13, the iron being universally pivoted at 14 in the end of a bar 15 slidably mounted in arm 16. The arm 16 is pivoted on vertical pivot 17 in the end of a pivoted pressure arm 18, said arm 18 being pivotally mounted at 19 in the bosses 20 (Fig. 2) extending upwardly from the top 1 of the frame. Arm 18 has its lower end pivotally connected at 21 to one end of a short link 22 which has its opposite end pivoted at 23 to one end of a lever 24. Lever 24 is pivoted between its ends at 25a to the lower end of a suspension link 26 having its upper end pivoted at 27 in bearing 28, formed on the underside of the top 1 of the frame. Near one of its ends, the lever 24 is pivotally connected at 25 to the upper end of a link 29 which has its lower end pivoted at 30 to a treadle 31. At its rear end, the treadle 31 is formed with a clevis 32 (Fig. 4) pivotally mounted on the shaft 33, supported in the bosses 34 on the sides 2 of the frame near the base thereof. A spring 35 has one end extending through an eye 36 on the underside of the top 1 of the frame, and its other end connected to the pin 37 secured in the end of lever 24 near pivot 25.

Through the mechanism thus far described, it will be apparent that when the foot plate 38, provided at the free end of the treadle 31, is depressed, link 29 will be drawn downwardly, said movement exerting a downward pull on the pivot 25 in lever 24, the opposite end of lever 24 rising to swing the lower portion of arm 18 rearwardly on an upward arc to cause arm 16 to bring the pressing iron 12 downwardly toward the buck 4. The means for adjusting the pressure of the iron 12 against a garment resting on the buck 4 will now be described.

At 39 is shown an adjusting link which has one of its ends pivotally connected at 40 to the dependent link 26 at a point between the pivots 25a and 27. The opposite end of adjusting link 29 receives the threaded end 41 of an adjusting screw 42, which is freely rotatably mounted in the front plate 10 of the machine and in member 47 and is provided with a handwheel 43 located at the front of the machine above the foot plate 55

38 of the treadle so that it is convenient for manipulation, whenever desired.

It will be obvious that by rotation of the hand wheel 43, the threaded end 41 moving through 5 the end of the adjusting link 39 may move the adjusting link longitudinally either to or from the front of the machine. When the adjusting link 39 is moved toward the front of the machine by rotation of hand wheel 43, it will swing the 10 link 26 on its pivot 27 in the same direction, this action tending to exert a similar pull on lever 24 which, through its connection with the lower end of arm 18 through link 22, will tend to swing said arm 18 on its pivot 19 in a counterclockwise 15 direction, as viewed in Figs. 1 and 3, so that the pressing iron 12 will be elevated and adjusted in a direction away from the buck. Thus, when pressure is applied on the treadle 38 to lower the iron 12, a lighter pressure of the pressing iron 20 12 on the buck will take place.

When the adjusting wheel 43 is rotated in a direction opposite to that just described or in other words, away from the front of the machine, a reverse action occurs. That is to say, the pressing iron is brought closer to the upper face of the buck and greater pressure of the iron thereon will 25 follow when the treadle 31 is depressed. Thus, by simple manipulation of the hand wheel 43, conveniently located at the front of the machine, 30 adjustment of the pressure imposed by the pressing iron 12 upon the buck can be had. I am aware that prior to this invention, adjustment means has been provided in pressing machines for regulating the pressure, but such adjusting 35 elements, and particularly the manually adjustable portions thereof, were inconveniently located and could only be operated with difficulty and delay by the operator. My improved adjusting means is located at the front of the machine 40 where, by simple turning of the wheel 43, hand adjustment of the pressing iron 12 over the goods supported by the buck can be attained.

A spring 44 surrounds the adjusting screw 41 and exerts friction to hold the screw in any set 45 position of adjustment.

When the foot plate 38 of the treadle is depressed, means is provided for holding the treadle in such depressed position, as shown in Fig. 1, for any desired period of time. Such means includes a gravity-operated latch member 45, pivoted at 46 at its upper end in supporting lugs 47, secured on the front 10 of the machine. Said latch member 45 is shaped to straddle the adjusting link 39 and at its lower end is provided 50 with the adjustable rod 48 arranged to have its lower end 49 engage one or the other of the notches 50 provided on the top of the treadle 31 to hold the treadle in its depressed position. When the treadle 31 is depressed as shown in 55 Fig. 1 by foot pressure imposed on the foot plate 38, latch member 45 will swing by gravity toward the right, when viewed as in Fig. 3, and the lower end 49 will engage in one or the other of the notches 50 on the treadle 31, the notch engaged being determined by the thickness of the goods 60 then being pressed. When the latch member 45 so engages one of the notches and is in position shown in Fig. 1, it will hold the treadle down 65 or in its depressed position as long as desired by the operator.

For releasing the latch member, I provide a bell-crank lever 51 which is pivoted at 52 between the walls of the slot 53 formed in treadle 31 near 70 the foot plate 38 thereon. The bell-crank lever

51 is formed with an upwardly extending weighted end 54 which rides against a downwardly-extending lug or plate 55 provided on the latch member 45. Bell-crank lever 51 has another arm 56 formed with an upturned end terminating in a button 57 movable through an opening 58 formed in the foot plate 38 of treadle 31. When foot plate 38 is depressed, the foot of the operator at the same time extends over and so depresses button 57 and this serves to 10 swing the weighted end 54 toward the right as viewed in Fig. 1, to permit the latch member 45 to also swing toward the right by gravity and engage one of the notches 50.

When it is desired to permit the treadle 31 to 15 rise and correspondingly move the pressing iron 12 away from the buck, the foot plate 38 of the treadle (but not button 57) is pressed downwardly near its free end for a slight distance, to permit the end 49 of the latch member to swing 20 toward the left under pressure of the weighted end 54 of the bell-crank lever 51, thus releasing the end 49 of the latch member from its engagement with one of the notches 50, and enabling the treadle 31 to be drawn upward under the 25 pull of the spring 35.

It will thus be clear that by foot pressure imposed on the foot plate 38, at the same time depressing the button 57, the treadle 31 will be forced downward to its lowered position, indicated at 51, which action causes the pressing iron 12 to descend upon the buck with pressure governed by the regulating screw 41. The latch member 45 automatically engaging one of the notches 50, will hold the treadle in its depressed 35 position as long as desired until the free end of the treadle is depressed, permitting the latch member to swing free of its engagement with the notch 50 under the pressure of the weighted end 54 of the lever 51.

The upper chamber 5 of the buck 4 communicates with a pipe 60 having its lower end connected to a valve chamber 61, in which valve 62 is mounted. A pipe or tube 63 connects the valve chamber with a suitable vacuum pump. Valve 45 62 is provided with a stem 64 which extends out of chamber 61 and is surrounded by spring 65 serving to normally hold valve 62 in closed position, thereby closing communication between chamber 5 and the vacuum pump. The lower 50 end of the stem 64 is pivotally connected at 66 to one end of a lever 67 which has its other end freely mounted on the pivot pin 30 extending through the treadle 31. Lever 67 is formed with a laterally extending lug 68 that overlies the top 55 of an arm 69 on a foot-operated lever 75 mounted on the pivot pin 52. Said lever has another arm 70 provided with a foot plate 71 located at one side of the foot plate 38 of treadle 31. The arm 70 is provided with a projecting lug 72 which extends beneath the foot plate 38 and is adapted to be contacted by a set screw 73, threaded downwardly through the plate 38 and caused to bear against the lug 72. A spring 74 surrounding the set screw 73 holds it in any selected position of 60 adjustment.

Briefly, the operation of the machine is as follows:

The operator places the article to be pressed over the buck 4 in the conventional manner and 70 applies foot pressure on the foot plate 38, his foot at the same time extending over and depressing the button 57. As the treadle 31 descends, under the pressure so imposed upon it, latch member 45 swings to the right as viewed in 75

Fig. 3 and its lower end 49 falls into engagement with one of the notches 50 in the top of the treadle 31. The device is then in the position shown in Fig. 1 where it will be seen that the treadle is held in its lowered or depressed position by the latch member 45, as just explained.

As the treadle descends, it carries with it the lever 75 bringing the end of arm 69 thereof away from the lug 68 on lever 67 so that during the descent of, and in its lowered position, the treadle 31 does not alter the position of valve 62 which remains closed. The descent of the treadle 31 brings the pressing iron 12 down on top of the goods with the desired pressure, regulated according to the adjustment of adjusting screw 41 and the operator can now manually move the pressing iron over the surface of the buck as desired, to press the article on the buck.

When the pressing is completed, the operator presses downward on the free end of foot plate 38 slightly, to disengage the latch member 45 from the notch 50, to thus permit, as previously explained, the treadle 31 to rise. As the treadle rises, the free end portion of arm 69 on lever 75 contacts lug 68 and swings lever 67 slightly upwardly on its pivot 30, to cause the valve stem 64 to be raised and the valve 62 to be opened, as shown in Fig. 3. Vacuum or suction exerted through the valve chamber 61 and pipe 60 draws moisture in the garment down through the holes 6 and out of chamber 5. The operation of the vacuum means just described, is primarily governed by means of the adjusting screw 73, and the setting of the same. That is to say, if the set screw 73 is unthreaded upwardly for a certain distance, the arm 69 on lever 65 will drop down by gravity and away from the lug 68 so that as the treadle 31 rises, the arm 69 will not contact with the lug and will not open the valve. Thus, by the setting of the set screw 73 the automatic operation of the valve opening means can be dispensed with. When the set screw 73 is adjusted as just explained, the operator can, however, at any time desired, impose pressure on the foot plate 31 of lever 75, causing the arm 69 to rise and lift the valve stem to open the valve. If he desires the valve to be automatically opened upon rising of the treadle, this can be done by the proper setting of set screw 73 which will bring the arm 69 of lever 75 in proper position to contact lug 68 as the treadle is raised to cause the valve to be opened.

The treadle 31 is provided with a bumper 30 which contacts against the lower end of link 26, said bumper being provided with a soft terminal portion 81 to contact with the end of link 26 as the treadle 31 rises.

With the machine described, the mode of operation is simplified considerably. The stroke of the foot lever or treadle being extremely short, the constant high lift of the foot required of operators in operating a machine of this type, is eliminated. While standing at the front of the machine, the operator can immediately, by simple rotation of the hand wheel, regulate the pressure imposed by the pressing iron to suit any particular portion of a garment or type of garment being pressed. He can also, by simple foot manipulation, provide automatic vacuum operation upon the rise of the treadle, this being found desirable by fast operators. At the same time, by simple adjustment of the set screw 73, manual control of the vacuum is had, so that the vacuum can be applied at any time during the pressing operation by the operator.

What I claim is:

1. In a pressing machine, a frame, a buck mounted over the same, a pressing iron located above the buck and mounted for movement to or from the buck, a pivoted arm for swinging the pressing iron to and from the buck, a treadle pivotally mounted in the frame, a linkage connection between the arm and the treadle, said linkage connection including a pivoted lever, a link suspending said pivoted lever from a portion of the frame, the lever being pivotally connected to said link, an adjusting member connected to the link, and means for adjusting said member back or forth in the frame to thereby shift the point of pivotal connection of the lever to the link 15 forwardly or rearwardly in the frame, and thereby move the pressing iron to or from the buck according to the position of the adjusting member.

2. In a pressing machine, a frame, a buck 20 mounted thereon, a pressing iron located above the buck, a pivoted arm on the frame carrying the pressing iron at one end and having a lower end extending downwardly in the frame, a treadle mounted in the frame, a pivoted link depending 25 downwardly in the frame, a lever connection between the lower end of said link and the lower end of the pressing iron supporting arm, means connecting said lever with the treadle whereby depression of the treadle will cause the pressing 30 iron to be moved toward the buck, an adjusting member connected to the link between its pivot and its connection to the lever, and means for regulating the position of said adjusting member to cause the same to shift the link on its pivot 35 and thereby control the position of the pressing iron with respect to the buck.

3. In a pressing machine, a buck, a pressing iron mounted above the buck, means for supporting the iron and moving it to or from the 40 buck, said means including a treadle adapted to be depressed to bring the iron toward the buck, means for holding said treadle in depressed position comprising a pivoted latch mounted above the treadle and having an end adapted to move 45 into a position above the treadle to prevent rise of the same, and a gravity-operated latch-control member pivoted on and carried by the treadle and acting to push the latch out of locking position when the treadle is pushed downwardly independently of the latch-control lever.

4. In a pressing machine, a buck, a pressing iron mounted above the buck, means for supporting the iron and moving it to and from the buck, said means including a pivoted treadle 55 adapted to be depressed to bring the iron toward the buck, means for retaining the treadle in depressed position, said means comprising a pivoted latch member mounted above the treadle and having a dependent free lower end adapted to 60 engage the treadle to prevent rise of the treadle when the treadle is in a depressed position, a latch control lever pivoted on the treadle and adapted for simultaneous foot depression in company with the treadle to thereby hold said control lever in an inoperative position during depression of the treadle to permit the latch to move by gravity into treadle-locking position, and means on the control lever for moving the latch out of locking engagement with the treadle 65 when the treadle is moved downwardly independently of the control lever while the latch is in position of treadle engagement.

5. In a pressing machine, a buck, a pressing iron mounted thereover, means for moving the 75

iron to or from the buck including a pivoted treadle, a latch pivoted above the treadle and adapted to move into position over the top of the treadle when the treadle is depressed to hold the treadle against rising movement, a latch control member comprising a weighted lever normally bearing against the latch and holding it in a position of disengagement from the treadle, said control member having means by which it may be rendered inoperative during the descent of the treadle to permit the latch to operatively engage the treadle, said control member being mounted for movement independently of the treadle whereby it may be rendered operative by downward movement of the treadle independently of the control member.

6. In a pressing machine, a buck, a pressing iron mounted above the buck, means for moving the pressing iron to and from the buck, said means including a treadle, means for creating suction within the buck to draw out moisture from a garment being pressed thereon, a valve interposed between the suction-creating means and the interior of the buck, means for normally holding the valve in closed position, and means

for automatically opening the valve at a pre-determined point in the movement of the treadle, said valve opening means including a pivoted lever carried by the treadle for opening the valve, and means also carried by the treadle for rendering said lever ineffective to open the valve during the movement of the treadle.

7. In a pressing machine, a buck and a pressing iron, means for moving the pressing iron to and from the buck, said means including a foot-operated treadle, means for creating suction within the buck to draw out moisture from a garment being pressed thereon, a valve for controlling the suction, means for normally holding the valve closed, means carried by the treadle and controlled by the movement thereof for opening the valve at a point in the movement of the treadle when the pressing iron is raised from the buck, and means for rendering the valve-opening means ineffective during treadle movement, but permitting independent manual operation of said valve-opening means to open the valve during movement or while the treadle is in a position of pause.

SAMUEL GOLDSTEIN. 25
